UNITED STATES PATENT OFFICE.

EDWIN WALKER, OF ERIE, PENNSYLVANIA.

PHONOGRAPH.

1,203,667.

Specification of Letters Patent. Patented Nov. 7, 1916.

Application filed September 25, 1907, Serial No. 394,584. Renewed March 30, 1916. Serial No. 87,875.

To all whom it may concern:

Be it known that I, EDWIN WALKER, a citizen of the United States, residing in Erie, in the county of Erie and State of Pennsylvania, have invented a certain new and useful Phonograph, of which the following is a specification.

This invention is a phonograph the carrier for the record of which is simultaneously rotated and given a traveling movement with respect to a relatively stationary reproducer.

According to one embodiment of this invention, the record-carrier is mounted on a traveling carriage, and with said carriage and the record-carrier are combined devices for simultaneously rotating the record-carrier and for feeding the carriage at a proper rate of speed, the movement of the carriage being a slow one as compared with the speed of the record carrier.

The carriage, its operating devices, and the driving means for the record carrier are simple and durable in construction, and operate with very little friction, wear and perceptible noise.

A broadly new feature of the instrument consists of means for simultaneously adjusting the reproducer and controlling the motor which operates the record-carrier, whereby records may be removed and replaced without scratching or mutilating them by the stylus of the reproducer, the latter being supported firmly in position and out of the way during such interchange of the records.

The reproducer which it is preferred to employ is of the character disclosed in my prior Patents No. 805,544 and No. 805,600, as well as in a copending application Serial No. 394,586, filed on even date herewith.

For the purpose of conveniently carrying the reproducer and the entire machine, it is preferred to provide a portable case in which the motor and working parts of the machine are installed permanently, said case being provided with compartments for the reception of the reproducer as well as of a number of records, etc.

As disclosed in the aforesaid patents and application, the reproducer is provided with a plurality of styli, and it is adjustable lengthwise for bringing either stylus into engagement with a record.

According to the present invention, the reproducer is, preferably, equipped with

means for supporting it firmly in either of several adjusted positions. Said supporting means restrains the reproducer from sidewise movement in a horizontal plane, but permits free movement in a vertical plane. One element of the aforesaid supporting means is foldable into compact relation with the reproducer when the latter is dismounted and packed in the aforesaid portable case, whereby the reproducer may be easily removed or replaced, as desired.

In the accompanying drawings, I have illustrated one practical embodiment of the invention, but the construction shown therein is to be understood as illustrative only, and not as defining the limits of the invention.

Figure 1 is a side elevation showing the portable case in an open position and the parts of the phonograph adjusted in position ready for use, the combined horn and reproducer being supported in a raised position with respect to the record carrier or mandrel, in order that a cylindrical record may be placed readily on said carrier or mandrel. Fig. 2 is a vertical cross section through the portable casing, showing certain parts of the machine in longitudinal section and side elevation, the combined horn and reproducer being illustrated in end elevation. Fig. 3 is a plan view of the portable casing and the phonograph, the horn and reproducer being removed. Fig. 4 is a vertical section on an enlarged scale and in the plane indicated by the dotted line 4-4 of Fig. 1 looking in the direction of the arrow, the reproducer and horn being omitted. Fig. 5 is a vertical section taken on the line 5-5 of Fig. 4 looking in the direction of the arrow. Fig. 6 is a detail cross section through a part of the carriage, showing the feed shaft and the feed lever or traveler which cooperates with said shaft, the plane of the section being indicated by the dotted line 6-6 of Fig. 2. Figs. 7 and 8 are views in side and end elevation illustrating another embodiment of the invention.

For convenience in transporting the machine and the records, I have shown a portable casing, A, which is provided with a hinged cover, a, adapted to be held in an open position by a brace, a', said cover when closed being locked in place by suitable fastenings, a''. The casing, A, is divided by partitions, b, b', into a plurality of com-

partments, B, B', B². The compartment, B, is adapted to receive the combined horn and reproducer, C, when the latter is dismounted from operative relation to a record. The compartments, B', B², provide for the storage of a number of records, and between said compartments is a motor casing, D, which contains the operating parts of the motor whereby the record is rotated on its axis and moved endwise with respect to the combined horn and reproducer.

Within the compartment, B², is mounted or secured a base plate, E, the same extending crosswise of the portable casing, A, at one end thereof. This base plate is provided with longitudinal parallel rods, e, e, which form a track for a sliding carriage, F. Said carriage is shown as consisting of the members, f, f, each of which is cast in a single piece of metal, substantially in the form represented in Fig. 6. The members of the carriage are joined rigidly together by appropriate longitudinal tie-rods, f', and said members are provided with the arched or curved upper end, f², each being formed with a depending perforated lug, f³, see Fig. 6. At the respective sides of the carriage are grooved rollers or wheels, e', e², the rollers, e', being adapted to ride upon the rods, e, of the track, while the rollers, e², ride against the underside of said rods, whereby the carriage is limited to sliding movement on the track, and the vibration of said carriage is minimized by the engagement of the rollers with said track. The carriage supports a record carrier, G, herein shown as a tapering mandrel for the reception of cylindrical records. Said mandrel is provided with a shaft, G', which extends lengthwise of the carriage and is journaled in the apertured lugs, f³, of the members, f, composing said carriage. The shaft, G', is mounted for rotation freely within its bearings of the carriage and it is moved endwise with said carriage, whereby the mandrel, G, is adapted for both rotary and endwise movement. The mandrel, G, is mounted on a shaft, G', and this shaft is provided with a longitudinal groove or key-way, g, in which works a spline or feather indicated by dotted lines at g' in Fig. 2, said spline or feather serving to operatively connect a driving pulley, G², with the mandrel shaft. This pulley is held from sliding with said shaft, G', by fitting it loosely between a pair of upstanding posts, h, which are made fast with the bed plate, E. It will be understood that the pulley, G², is driven by the motor for the purpose of rotating the shaft, G', and the mandrel thereon, but as said shaft and mandrel are moved endwise by a feed mechanism, to be presently described, the pulley, G², is restrained by the posts, h, from sliding with said shaft, whereby the pulley which imparts rotary motion to the mandrel has

a fixed or predetermined relation to the motor.

I designates a feed shaft which is journaled in appropriate bearings, e³, of the bed plate, E, said shaft being preferably below the mandrel shaft, G', parallel thereto and extending loosely through the members, f, of the traveling carriage. It is preferred to provide a coarse male thread, i, on this feed shaft, and with said male thread engages a feed lever or traveler, I'. Said traveler is pivoted at one end, as at i' to the carriage, see Fig. 6, and the lever is notched at a point intermediate of its ends, as at i², whereby the lever fits snugly to the feed shaft, I, and is adapted to work in the thread thereof. Said lever is held in engagement with the thread of the feed shaft by a coiled spring, I², one end of which is fastened to the free end of said lever, and the other end is anchored at a fixed point within the portable case, A. The principal function of this spring is to impart endwise movement to the carriage which carries the rotating record, and said spring thus takes off the motor or driving mechanism the labor of propelling the carriage. In this connection it is to be noted that the carriage, while actuated by the spring, is controlled by the feed shaft, and this shaft is operated by the motor, the functions of said motor being, mainly, to rotate the mandrel and the feed shaft.

It is evident, that the lever, to which the spring is attached, may be lifted by hand from engagement with the screw shaft, for the purpose of moving the carriage without hindrance from the shaft in one direction or the other, thus permitting the carriage and the record to be easily and quickly returned to a starting position.

The feed shaft, I, is provided with a pulley, I³, which is adjacent to and below the pulley, G², on the mandrel shaft. Said pulleys, G², I³, are driven by belts, G³, I⁴, see Fig. 3, said belts being operated by pulleys, G⁴, I⁵, of the motor, see Fig. 4.

The combined horn and reproducer, C, is of the shape more particularly shown in Figs. 1 and 2, said horn and reproducer being constructed as disclosed in my prior patents and in a copending application filed on even date herewith, Serial No. 394586. The element, C, is provided with a plurality of styli, c, which are fixed to the base of the reproducer, near the closed rear part thereof, and said reproducer is mounted for adjustment longitudinally of the casing, whereby either of the styli, c, may be brought into engagement with a record on the mandrel, G. The reproducer is provided at its front portion with a supporting bracket, J, the upper part of which is connected pivotally at j to a plate, j', the latter being fixed to a rib, c', at the mouth portion of the reproducer. This supporting bracket is foldable

- within the open mouth of the reproducer when the latter is dismounted from the machine, and is adapted to be stored within the compartment, B, of the portable case. The 5 supporting bracket is adapted to be fitted adjustably on the portable case, A, by any suitable means, but it is preferred to construct said supporting bracket in a way to hold the reproducer, C, from vibration sidewise, and at the same time, secure the necessary longitudinal adjustment of the reproducer, while permitting it to vibrate on the horizontal axis afforded by the pivot, j. As 10 shown in Fig. 1, the supporting bracket, J, is provided with a longitudinal socket, j², in which is adapted to be fitted either of the supporting pins or stems, J'. Said stems are attached or made integral with a plate, J², and the stems are spaced on said plate 15 at intervals corresponding to the intervals between the styli, c. The plate, J², is fastened to the casing, A, in a suitable way, and the upper edge of said plate projects above the corresponding edge of the casing. The 20 bracket, J, is provided with an angular foot piece, J³, which is forked as at j³ so as to embrace the projecting top edge of the plate, J². When the reproducer is mounted for the bracket, J, to fit on the first stem, J', 25 the forked foot, J³, engages with the plate, J², and the first stylus, c, is adapted to rest on the record of the mandrel, G. To bring the second stylus into position for operation, the bracket, J, and the reproducer are lifted 30 so as to withdraw said bracket from the first stem, after which the bracket may be slipped over the second stem, J², and locked into position for the foot to again engage with the plate, whereupon the second stylus is in 35 position for coöperation with the record. This adjustment of the reproducer and its supporting bracket may be performed to bring the third stylus into coöperative relation with the record, but it is to be noted 40 that in either of the several positions of the reproducer the foot, J³, of the bracket is adapted to engage with the plate, J², for holding the reproducer against sidewise movement.
- 45 In Figs. 4 and 5 of the drawings, I have shown one form of motor which has been found to give good results in practice, but it is to be understood that I do not intend to restrict myself to the use of any particular form of motor, for the reason that said motor may be modified and changed within wide limits. As shown, the driving spring, K, is anchored at one end within the casing, D, but the other end of this spring is made 55 fast with a disk or drum, k, or said end of the spring may be secured rigidly to the main driving shaft, L. Said shaft is mounted in suitable bearings within the casing, D, and in one side of the casing, D, or the portable case, A, is an opening, l, which is in 60 alignment with the end portion of the main shaft, L, whereby a key or crank may be introduced through said opening and engage with an end portion of the shaft, L, for the purpose of turning the latter in order to 65 place the driving spring, K, under tension. As is usual in the art, a detent mechanism, such as a pawl and ratchet (not shown) is employed for holding the driving spring against unwinding. On this shaft, L, is 70 rigidly secured the driving pulley, I⁶, which operates the feed shaft, I, at the required speed. Said shaft, L, is provided with a gear, m, which meshes with a pinion, m', on a counter shaft, M, and this counter shaft 75 is provided with a gear, n, which meshes with a pinion, n', on a shaft, N. Said shaft is provided with a gear, o, having intermeshing engagement with a pinion, o', on a short shaft operating the centrifugal governor mechanism, O, the latter being of any suitable or preferred construction. Said governor operates a brake disk, p, with which is adapted to engage a suitable form 80 of regulator for controlling the speed of the motor, and consequently the speed of the pulleys which operate to impart the sliding and rotary movement to the mandrel, G.
- 85 The driving pulley, G⁴, which operates the belt, G³, for rotating the mandrel is carried by the shaft, N, and the shafts, L, N, are so arranged for operation that the carriage, F, will be moved endwise at the required speed and the mandrel, G, will be operated at a different speed, whereby the 90 record is moved endwise and rotated simultaneously to operate the reproducer.
- 95 One of the important features of my new machine is a combined reproducer support and stop mechanism for the motor, said device operating to lift the reproducer from the record simultaneously with the stoppage of the motor, and vice versa, said mechanism operates to start the motor simultaneously with the adjustment of the reproducer into 100 coöperative relation with the record. Various devices may be employed for performing this function, but in Figs. 4 and 5 of the drawings, I have shown a simple and effective means for this purpose. A brake lever, P, is arranged within the motor casing, D, and said lever is fulcrumed at p' on a fixed bracket arm, p². The lever is provided with a depending arm, q, which carries the brake shoe, q', of leather, felt or other material, 110 said brake shoe being supported opposite to the brake disk, p, of the centrifugal governor, see Fig. 4. The lever, P, extends upward to the top portion, d', of the motor casing, and said end of the lever is connected by a screw, r, with a slide, R, the latter resting upon the top, d', of said motor casing. Said slide is provided on its underside with a rib, r', arranged to work in a slot, r², of the motor casing, and the slide is 115 120 125 130

equipped with a bent arm, S, which extends upwardly from the slide, and is preferably curved to form a seat on which is adapted to rest the underside of the reproducer, C. The 5 slide is movable in the slot, r^2 , of the motor casing, and the range of adjustment of the slide is regulated by a stop, s, which is fitted in the slot, r^2 , and is adapted to be fixed at different points therein by a screw, s', said 10 stop being in the path of the slide, R. The slide, R, may be moved in the slot, r^2 , for the purpose of adjusting the seat, S, below the reproducer, C, for the purpose of supporting said reproducer in a raised position 15 wherein the styli are above the path of the record, substantially as shown in Fig. 1, said reproducer turning on the pivot, j, when the rest, S, is thrust beneath it. Said inward movement of the slide and seat turns 20 the lever, P, on its fulcrum, p', and moves the brake shoe, q', into engagement with the brake disk, p, whereby the inward movement of the slide, R, simultaneously brings the seat, S, into engagement with the reproducer and applies the brake shoe, q', against the disk, p, for the purpose of arresting the governor, O, and the motor. The reproducer is adapted to be supported by the seat, 25 S, in a position wherein the styli, c, are 30 above the record, and as the mandrel, G, is at rest, a record may be withdrawn from said mandrel and a new record placed thereon, such interchange of the records being effected without danger of scratching or 35 mutilating the records.

The mandrel, G, and the reproducer, C, are at right angles to each other, said reproducer extending lengthwise of the portable case, A, and said mandrel being moved end- 40 wise in a path at right angles to the reproducer. Such arrangement and operation of the parts is quite desirable when the entire machine is to be carried or packed in a portable case, but it is to be understood that the 45 invention is not confined to the employment of a record mandrel movable in a path at right angles to the axis of a reproducer. In Figs. 7 and 8 of the drawings, I have shown a phonograph wherein the cylindrical end- 50 wise movable mandrel is arranged in a parallel relation to the reproducer, the said mandrel being movable lengthwise in a path parallel to the longitudinal axis of said reproducer. The mandrel is carried by a shaft, 55 G', which is mounted in a carriage, F, and said carriage is moved endwise by a feed shaft while the mandrel is rotated from the motor by a pulley, all as heretofore described. The reproducer, C, may be equipped 60 with a single stylus, c, or with a plurality of styli, and said stylus of the reproducer is adapted to rest on the record, Z, at a point located to one side of the vertical plane of the mandrel shaft, see Fig. 8. This relation 65 of the reproducer to the mandrel prevents

the stylus from sliding in one direction off the record, but the movement of the reproducer in the other direction is limited by a suitable anchor herein shown as an arm, T, one end of which is pivotally connected as at 70 t to the reproducer, while the other end is pivoted at t' to a fixture, T', adapted to be fastened to the motor casing, D.

The apparatus shown in Figs. 7 and 8 is operated in practically the same way, and by 75 the same means, as the structure shown in the other figures of the drawings, except that the record is moved endwise in a path substantially parallel to the longitudinal axis of the reproducer and horn. In this 80 connection attention is called to the fact that the record mandrel is mounted on the carriage, F, for movement below and lengthwise of the reproducer and horn, and in connection with the last named element, I employ the combined support and brake. The support, S', of Fig. 8 is adapted for engagement with the arm, T, for the purpose of lifting the arm and the reproducer when the brake is applied to arrest the motor, but a 85 reverse operation takes place, as heretofore described, when the support and brake are adjusted, whereby the support lowers the reproducer on the record simultaneously with the operation of releasing the brake. 90

Having thus fully described the invention, what I claim as new, and desire to secure by Letters Patent is:

1. In a phonograph, a reproducer, a record carrier, a motor for operating one of 100 said parts, a brake element separate from the record carrier, said brake element being rotated by the motor, and a combined brake and reproducer support coöperating with the motor driven brake element and with 105 the reproducer, whereby an adjustment to one position of the combined brake and reproducer support operates to separate the reproducer and the record carrier relatively to each other and to apply the resistance 110 of the brake to the motor.

2. In a phonograph, a relatively stationary reproducer, a mandrel shaft adapted to carry a record mandrel, a motor including a 115 rotatable brake element, said brake element being separate from the record mandrel, means operated by the motor for imparting to the mandrel shaft and the record mandrel a slidable and rotative movement relative to the reproducer, and a combined brake 120 and reproducer support coöperating directly with the motor-driven brake element and with the reproducer.

3. In a phonograph, a non-traveling reproducer, a mandrel shaft adapted to carry 125 a record mandrel, a motor, means operated by the motor for imparting to the mandrel shaft and the record mandrel a slidable and rotative movement relative to the reproducer, a brake element separate from the rec- 130

ord mandrel, said brake element being operated directly by the motor, and means co-operating with the motor driven brake element and with the reproducer whereby the 5 reproducer may be moved relatively to the record mandrel and the motor arrested at one operation.

4. In a phonograph, a non-traveling reproducer, a mandrel shaft adapted to carry 10 a record mandrel, a motor, means operated by the motor for imparting to the mandrel shaft and the record mandrel a slidable and rotative movement relative to the reproducer, a brake element separate from the record mandrel, said brake element being rotated directly by the motor, a second brake member co-operating with the rotatable brake member, a reproducer support movable to a position for lifting the reproducer from 15 contact with a record on the record mandrel, and means connecting the reproducer support with the second brake member, whereby the adjustment of the reproducer support to one position operates the connecting 20 means to apply the second brake member to the record mandrel, and means connecting the reproducer support with the second brake member, whereby the adjustment of the reproducer support to one position operates the connecting 25 means to apply the second brake member to the rotatable brake member.

5. In a phonograph, a non-traveling reproducer, a mandrel shaft adapted to carry 30 a record mandrel, a motor, means operated by the motor for imparting to the mandrel shaft and the record mandrel a slidable and rotative movement relative to the reproducer, a brake element separate from the record mandrel, said brake element being 35 rotated directly by the motor, a second brake member co-operating with the rotatable brake member, a slidable reproducer support movable into and out of engagement with the reproducer, and a brake lever intermediate the reproducer support and the 40 second brake member for applying the latter to the rotatable brake member when the reproducer support lifts the reproducer from co-operative relation with the record mandrel.

6. In a phonograph, a non-traveling reproducer, record supporting means, driving 45 mechanism therefor, a rotatable brake member separate from the record support and operated directly by the driving means, a manually operated reproducer support slid- 50 able beneath the reproducer and adapted to lift the latter from a record, a second brake member co-operating directly with the rotatable brake member, and a lever intermediate the second brake member and said reproducer support.

7. In a phonograph, a non-traveling reproducer, record supporting means, driving 55 mechanism therefor, a rotatable brake member separate from the record support and operated by the driving means, a manually operated reproducer support operable at will to lift the reproducer from co-operative 60 relation with said record supporting means,

and a brake lever connected directly with said reproducer support and co-operating with the rotatable brake member.

8. In a phonograph, a nontraveling reproducer, a carriage mounted for sliding movement relative to said reproducer, a shaft mounted on the carriage for rotation thereon and for sliding movement therewith, a record mandrel mounted on the shaft, a feed shaft operatively connected 70 with the carriage for the purpose of imparting sliding movement thereto, a motor, a driven member mounted on the mandrel shaft and rotatable with said shaft, said driven member co-operating with the motor 75 and with the mandrel shaft for the purpose of rotating said shaft, means for restraining the driven member from partaking of the sliding movement of the mandrel shaft, and a separate driving connection intermediate 80 the motor and the feed shaft.

9. In a phonograph, a feed shaft having a coarse male thread, a traveling carriage, a feed lever fulcrumed on the carriage and fitting the thread of said shaft, and a spring 90 connected to said feed lever and acting in a two-fold capacity to retain the feed lever in engagement with the threads of the feed shaft and to propel the traveling carriage in a given path.

10. In a phonograph, a feed shaft having a male thread, a carriage, a feed lever extending crosswise of the shaft and positioned above the same, said feed lever engaging with the thread of the shaft and adapted 100 to be lifted at will free from engagement therewith, and a spring for applying tension to the feed lever whereby the carriage is moved in one direction and the lever is retained in operative relation to the feed 105 shaft.

11. In a phonograph, a bed plate having a track, a carriage slideable on the track, a feed shaft extending through the carriage and connected operatively therewith, a mandrel shaft mounted on the carriage, fixed 110 posts through which the mandrel shaft is adapted to slide, and a pulley splined on the mandrel shaft and restrained by the posts from sliding therewith.

12. In a phonograph, a non-traveling reproducer, a carriage slideable relatively thereto, a record-carrier mounted on said carriage for slidable movement therewith, a spring for directly moving said carriage 120 in one direction, means for controlling the travel of said carriage under the action of said spring, and means for rotating the record-carrier at the same time it partakes of the sliding movement of the carriage relative to the reproducer.

13. In a phonograph, a non-traveling reproducer, a traveling record-carriage, a slideable and rotatable record carrier mounted 125 on said record carriage, tension means co- 130

operating with the record-carriage for imparting traveling movement to the record carrier relatively to said reproducer, motor-driven feed mechanism for regulating the travel of said record-carriage, means for rotating the record carrier simultaneously with the feed motion of said record carrier with the carriage, and means for stopping the feed mechanism and for shifting the reproducer from operative relation to the record carrier.

14. In a phonograph, the combination of a traveling carriage, carriage controlling means associated therewith, means for actu-

ating the carriage controlling means, means connecting the carriage to the carriage controlling means, and tension means for automatically maintaining the connecting means in operative position and simultaneously imparting sliding movement to the carriage. 15
20

In testimony whereof I have signed my name to this specification in the presence of two subscribing witnesses.

EDWIN WALKER.
